OLE ROLFSEN, OF LARVIK, NORWAY.

ROTATING TOOL FOR WORKING IN EARTH, ROCK, METAL, WOOD, AND THE LIKE.

Original application filed December 17, 1925, Serial No. 75,986, and in Norway December 23, 1924.
 Divided and this application filed February 1, 1928. Serial No. 251,208.

The present invention relates to tools for working in earth, rock, metal, wood and the like and more particularly to tools which comprise discs mounted on a rotating shaft 5 and having hammer heads in connection therewith.

The hammer heads may be given a polygonal form, such as, for example, a triangular form and are provided with a center opening having approximately the same polygonal form as the outside edge of the hammer. Due to the conformation of the center opening the hammer head is adapted to take up a definite number of positions on a pin on which 15 the hammer is mounted. The pin is connected to the rotating disc by means of members such as, for example, levers or arms.

For an example of apparatus adapted for carrying out the invention reference is made 20 to the accompanying drawing in which;

Figure 1 is a vertical view of the cutting tool;

Fig. 1^a is a similar view of a modification.

Fig. 2 is a side view of the cutting tool; and

25 Fig. 3 is a detail view of a modified part of the construction.

Referring to the drawings, Figure 1^a shows a tool which comprises a main shaft 10, and a disc 11 mounted thereon in any appropriate 30 manner. The disc 11 is provided with indentations 12 in its outside curvature for the hammers. The levers 13 and 14 are pivoted to both faces of the disc near the indentations 12. These levers 13 and 14 are provided with 35 slots 15. The pins 16 pass through these slots thereby forming a slidable connection with

said levers. The pins 16 may be provided with suitable means such, as for example, the heads or shoulders 17 to keep said pins in position.

40 The portion of the pins disposed in the slots of the levers may be provided, if it is found desirable, with friction resisting elements, such as, for example, the bearings 18. Likewise, if desired, the levers 13 and 14 may

45 be counterbalanced by extensions 19 (Figure 1) in order to reduce the stress on the pins 16 when the disc 11 is rotated. In order to limit the motion of the levers and the pins toward the center of the disc, the disc is provided

50 with the projections 20 which limit the outward movement of the extensions 19 (Figure 1) of the levers. The hammer heads 21 are of triangular form with a center opening 22 having approximately the same form. The

hammer heads 21 are mounted on the pins 16 55 between the levers. The center openings 22 engage the pins 16 and are dimensioned so as to allow the hammer heads a certain amount of loose play on the pins. The indentations 12 are made sufficiently large so as to allow 60 free rotation of the hammer heads on the pins 16.

When the disc 11 is rotated, the pins and hammer heads will be held in their extreme outward position, the stress on the pins being 65 reduced to a minimum by the counterbalancing effect of the extensions 19 of the levers. If the hammers should strike an obstacle, the pins may be pressed radially inwards due to the construction of the slots in the levers but 70 will return immediately to the outward position due to the centrifugal force acting on the hammer heads.

The levers 13 and 14 may be replaced by the arms 23 and 24 shown in Fig. 3, the arm 75 23 being provided with a yielding link such as, for example, the bolt 25 and the helical spring 26.

In the drawings, the disc 11 is equipped with only two hammer heads but it is evident 80 that by increasing the size of the disc or by decreasing the dimensions of the levers and hammer heads, the disc may be provided with a greater number of hammer heads.

This application is a division of my previous 85 application for a "rotating tool for working in earth, rock, metal, wood and the like", Serial No. 75,986, filed December 17, 1925.

I claim:

1. A rotating tool for working in earth, 90 rock, metal, wood and the like which comprises a disc mounted on a rotating shaft, hammer heads rotatably mounted with loose play on pins, lever rotatably mounted on 95 said disc and adapted to hold said pins so as to allow them to move radially with respect to said rotating shaft.

2. A rotating tool for working in earth, 100 rock, metal, wood and the like which comprises a rotating shaft, a disc on said rotating shaft, levers pivoted to said disc, pins connected to said levers, said levers being adapted to allow said pins to move radially with respect to said rotating shaft, and hammer heads rotatably mounted with loose play 105 on said pins.

3. A rotating tool for working in earth,

rock, metal, wood and the like which comprises a rotating shaft, a disc on said rotating shaft, levers pivoted to said disc, pins mounted in slots in said levers so as to allow said pins to move radially with respect to said rotating shaft, and hammer heads rotatably mounted with loose play on said pins.

4. A rotating tool for working in earth, 10 rock, metal, wood and the like which comprises a rotating shaft, a disc on said rotating shaft, levers pivoted to said disc, pins mounted in slots in said levers so as to allow said pins to move radially with respect to 15 said rotating shaft, counter weights on said levers to relieve the stress on said pins during rotation of the shaft and hammer heads rotatably mounted with loose play on said pins.

20 5. A rotating tool for working in earth, rock, metal, wood and the like which comprises a rotating shaft, a disc on said rotating shaft, levers pivoted to said disc, pins mounted in slots in said levers so as to allow 25 said pins to move radially with respect to said rotating shaft, counter-weights on said levers to relieve the stress on said pins during rotation of said shaft, means for limiting the inward motion of the pins towards the shaft

and hammer heads rotatably mounted with 30 loose play on said pins.

6. A rotating tool for working in earth, 35 rock, metal, wood and the like which comprises a rotating shaft, a disc on said shaft, indentations in the circumference of said disc, levers pivoted on said disc, pins connected to said levers, said levers being adapted to allow said pins to move radially 40 with respect to said rotating shaft, means for limiting the inward motion of the pins towards the shaft and hammer heads mounted with loose play on said pins.

7. A rotating tool for working in earth, 45 rock, metal, wood and the like which comprises a rotating shaft, a disc on said shaft, indentations in the circumference of said disc, levers pivoted on said disc, pins mounted in slots in said levers so as to allow 50 said pins to move radially with respect to said rotating shaft, counter-weights on said levers to relieve the stress on said pins during the rotation of said shaft, and hammer heads rotatably mounted with loose play on 55 said pins, said indentations being dimensioned so as to allow said heads to rotate freely on said pins.

In testimony whereof I affix my signature.
OLE ROLFSEN.
